Fair or Better INVENTOR

UNITED STATES PATENT OFFICE.

ISIDOR KITSEE, OF PHILADELPHIA, PENNSYLVANIA.

TELEPHONY.

SPECIFICATION forming part of Letters Patent No. 691,060, dated January 14, 1902.

Application filed April 15, 1901. Serial No. 55,939. (No model.)

To all whom it may concern:

Be it known that I, ISIDOR KITSEE, of the city and county of Philadelphia, State of Pennsylvania, have invented certain new and 5 useful Improvements in Telephony, of which the following is a specification.

My invention relates to an improvement in telephony, and has more special reference to an improvement in party-lines.

- 10 In a telephonic system of to-day, consisting of a central or exchange station and a series of outlying or subscribers' stations, the custom prevails of providing two or more subscribers whose phones are very seldom 15 busy—for instance, in dwelling-houses—with one common circuit. These lines are called "party-lines." Efforts were made to prevent on such lines one subscriber from listening to the conversation of a second subscriber. So, 20 also, were efforts made to prevent the alarm of one subscriber ringing if another subscriber is called up by the central. In practice so far all these efforts have proved not very successful, especially not if a great number of subscribers—25 for instance, six, eight, and ten—are connected to one and the same line. A party-line to be successfully operated should be provided with devices as follows: First, a device to prevent the calling up of central by a subscriber if the line is already busy—that is, if a 30 second subscriber has already called up central or is connected by central with another line for the purpose of intercommunication; second, a device to prevent one subscriber 35 from listening to the conversation of a second subscriber if this second subscriber does not wish to communicate with the first-named subscriber; third, a device to prevent the alarm of one subscriber ringing if the office calls up a 40 second subscriber, and, fourth, a device to allow central to place two subscribers on the same line in intercommunication with each other and to ring up for that purpose one of these two subscribers after the other of these 45 two subscribers has called the central for this purpose. All of the efforts made so far have, besides others, the great disadvantage that normally all of the individual subscribers' circuits connected to one and the same line 50 are normally closed and in multiple arc as to each other and the current-carrying circuit. In my experiments I have found that it is

hardly possible to successfully transmit messages over a line-wire having two or more stations normally closed and connected in multiple arc as to each other. 55

It is the aim of my invention to overcome all these difficulties and to provide a party-line with all the advantages enumerated.

Referring now to the drawings, Figure 1 is 60 a diagrammatic view showing two subscribers' stations, one of the subscribers having removed the receiver from the lever. Fig. 2 is a diagrammatic view of the device placed at the central station. 65

1 and 2 are the circuit-wires.

1^a is part of the circuit-wire 1 turned backward for the purpose as will be hereinafter specified.

3 represents the transmitters of each station; 4, the receivers; 5, the levers on which the receivers are normally supported. This lever is electrically connected through wire 7 with the line-wire 2. 70

6 is a contact-point designed to connect with 75 the lever 5 when the receiver is removed. Lever 5 is preferably provided with the indentation, as shown in the drawings, adapted to receive the lower point of the contact 6 if the receiver is removed. 80

Inserted in series in line 1 is for each station the electromagnet 12. This electromagnet is provided with the armature 9, normally held by spring 11 away from the core of said magnet. This armature is provided with a 85 non-conducting piece 10.

Connected to the line-wire 2 through wire 35 is the alarm device 13. The coils of the electromagnet of this alarm consist of two parts connected in a manner so that they normally oppose the action of the current on the armature. It is unnecessary for me to refer more specifically to the connection of the coils, as it is well understood by persons versed in the art how to wind the electromagnet of an alarm device so that the two parts of the windings are opposed to each other in a manner so that the influence of the electric impulses on the core should be nullified. Normally, therefore, if a current is sent through wire 35 and through both pairs of the coils of the alarm device 13 this alarm device will not be actuated, and to ring this device it is necessary to shunt one pair of these coils, and 90 95 100

for this reason these coils are provided with the shunt-wires 13^a 13^a, terminating in the brushes 23 23. In series with the alarm device 13 is placed the electromagnet 19, provided with the armature 17, held away from the core of said electromagnet by spring 18. This armature is provided with the pawl 16, constituting, with the wheel 14, a modification of the well-known step-by-step devices. This wheel is provided with the teeth 15 and the insulation 20; but each wheel has at a predetermined point the insulation cut away for the purpose as will hereinafter be specified. These points are numbered 21 and 22, respectively. These points 21 and 22 differ in location in the wheels of the various stations. The wire 35, with its alarm device 13 and electromagnet 19, is grounded at G.

To the wire connecting contact 6 to the receiver 4 is connected wire 24, terminating in one of the contact-brushes 24^a. The other of these contact-brushes 24^a is connected to contact-point 8 in proximity to the lever 5.

In Fig. 2, B is the battery normally connected to the circuit. 25 is a contact-point electrically connected with one arm of the spring-jack, consisting of the two arms 26 and 27. 29 is a plug connected by the cord with the conducting-rim 31 of the make-and-break device 30, the movable lever 33 of which is connected with the battery B², grounded at G'. To the conducting-rim 31 are connected the contacts 0 to 14, inclusive.

In a party-line in which two or more subscribers' stations are connected it is of importance that the operation in one station should affect all the instruments in every other station in a manner so that the same cannot be used for telephonic purposes. If this circuit consists only of two line-wires and if the devices actuating the different stations in a manner as aforesaid are to be placed in series, it is obvious that if the subscriber nearest to the central removes his receiver for the purpose of calling up central the other devices will not be actuated at all, for the reason that the transmitting and receiving instruments are placed in multiple arc and the current therefore would take the shortest cut and return to the central without flowing through the devices of the other stations. For this purpose it was necessary that one of the line-wires (in the drawings line 1) should be turned back in a manner as indicated in Fig. 1. This short wire (designated in the drawings as 1^a) is not in reality a third wire. Supposing that the particular party-line is carried five miles from the central and at the end of the five miles the different subscribers to be connected to this line are located in one and the same house or in one and the same block, then that part of the wire designated by 1^a needs to run only along the block or house, as the case may be. In other words, the turned-back part of wire 1 should only run from the location of the first to the location of the last subscriber. Normally—

that is, when none of the stations are in use—the circuit consisting of line-wire 1 and of line-wire 2 is entirely open. No device placed in multiple arc as to this circuit is connected normally with both wires, and therein lies the first advantage of my invention. In a party-line to the circuit of which two or more subscribers are connected in multiple arc it is necessary that the devices and arrangements of same should be entirely alike, and if the devices are normally connected, even, as is usually the case, through condensers, with both lines, then it follows if one party tries to communicate with the central or through same with a subscriber on another line all or part of the transmitting-waves will be shunted through the devices of the other stations, because it is a well-established fact that, concerning telephonic waves, condensers are no hindrance at all. As long as all stations are at rest the wire 1 will be connected to one pole of the common battery at the central, and the wire 2 will be connected to the other pole of the same battery. The circuit itself will remain open, for the reason that as long as the receiver rests on the lever the connection between the lever and the contact 6 is broken.

I will now describe the operation of the device placed in the line when one of the subscribers is calling.

The subscriber in the act of calling removes his receiver from the lever, and the lever, released of its weight, will press upward, and the lower part of the contact 6 will be inserted in the notch with which the lever is provided, thereby establishing a path for the current from the battery through wire 1, wire 1^a, transmitter 3, receiver 4, contact 6, lever 5, and line-wire 2 back to the battery. As soon as the current-flow commences the cores of electromagnets 12 will be energized, and the armatures of these magnets will be drawn toward their respective cores and in a position as indicated in the drawings at the left-hand station—that is, the non-conducting part 10 of the armature will be pushed between the contact 6 and lever 5. The armature of the particular station calling will always tend to assume the position of the armatures of the other station and to place the non-conducting piece 10 between the contact 6 and the lever 5; but as the contact has to be inserted in the notch of the lever before the circuit is established and before the cores are energized it is obvious that the position of the lever 5 at that particular station will effectually prevent the armature from assuming the perpendicular position and from inserting the non-conducting piece between itself and the contact-point. The subscriber calling has a free path to the central; but if at one and the same time or during the conversation of the subscriber calling a second subscriber attempts either to call up central or to listen to the conversation of the first subscriber and in this attempt removes his receiver the lever in its

upward movement will encounter the non-conducting piece 10, which effectually bars its electrical connection with contact 6. It is therefore obvious that no matter how many 5 subscribers are connected to one and the same line only one subscriber can at one and the same time converse with the central or through the central with a subscriber on another line and that no other subscriber can 10 listen to the conversation of the subscriber talking.

I will now describe the *modus operandi* of calling up one of the subscribers connected to this party-line.

15 At the central is placed the make-and-break device 30. This make-and-break device consists, preferably, of the conducting-rim 31 and a series of contact-points connected to said conducting-rim. The make-and-break device 20 vice is provided with the movable lever 33. I have illustrated in the drawings the movable lever as to be adapted to be moved by hand; but it is obvious that this lever may be 25 actuated by any of the well-known motive powers. Normally the lever rests, as is shown in the drawings, at zero—that is, at the contact-point 0. If central wants to call a subscriber connected to the line, the operator first ascertains what particular number on 30 that line the subscriber to be called has. Suppose in this line there are fourteen subscribers and the one to be called up is the fourth on the line—that is, is designated by the numeral 4. The operator connects the line- 35 wire 2 through plug 29 with the conducting-rim 31 and then moves the lever 33 from the contact-point 0 to the contact-point 4. This operation will break and make the circuit four times. At each subscriber's station 40 is located the step-by-step movement as described above. This step-by-step movement is provided with two pairs of contact-brushes, (designated, respectively, 23 and 24^a.) The contact-brushes 23 are designed, as clearly set 45 forth above, to shunt that part of the coil of the alarm device 13 which neutralizes normally the effect of the current flowing through said device. Let us suppose that the left-hand station is the station 4 called up by the 50 central. The step-by-step movement at this station will be actuated till the conducting part 22 of the wheel 14 comes in contact with the brushes 23, thereby short-circuiting the brushes and through them the opposing parts 55 of the coils of the alarm device 13. The operator at the central having moved the lever of the step-by-step device to point 4 connects the terminal of his magneto-generator with wire 2 of the circuit, the other terminal of the 60 generator being connected to the ground. The alternating impulses of the generator will therefore flow through wire 2 and will pass out each station from wire 2 through wire 35, coils of alarm device 13, and electromagnet 65 net 19 to the ground. These alternating impulses are not of sufficient duration to operate the electromagnet 19; but they are of suf-

ficient electromotive force to operate the alarm device 13. In all stations with the exception of station 4, wherein through the electrical connection of the brushes 23 the opposing coils are shunted, the electric impulses will flow through both pairs of coils of the alarm device 13, and, as described above, the action of these coils is such as to neutralize 70 the effect of the current on the core. It is evident that all the alarm devices, with the exception of the alarm device of station 4, will remain silent, but the alarm device of station 4 having only one set of coils in active 80 service, the other set of coils being shunted, will be actuated and the bell will ring, calling the attention of the subscriber of station 4 that the office wants to communicate with him. No matter, therefore, how many subscribers are connected to the line, only the alarm device of the subscriber with which the central wishes to communicate will be 85 actuated.

I will now describe the steps necessary for 90 the purpose of advising one subscriber that a second subscriber on the same line wishes to communicate with him.

The subscriber calling goes through the operation as described, removing his receiver from the lever 5 and bringing the lever in connection with contact 6. He makes, as usual, the operator at the central acquainted with his wishes. The operator in calling up another subscriber on the same line acts in 100 the same manner as if a subscriber of another line has called up this subscriber. It is again supposed that subscriber No. 4 is being called. The operator moves the lever from the contact 0 to contact 4. This brings again the 105 wheel in such a position that the contact 22 connects the brushes 23, shunting the opposing coils of the alarm device 13. The operator again rings up the station 4. The subscriber in answering the call removes his 110 phone from the lever and allows the same to resume a position as indicated in the right-hand station of the drawings; but the lever will not be able to make an electrical connection with contact 6, because the non-conducting material 10 has already assumed a position as indicated in the left-hand station of 115 the drawings. To obviate this difficulty and to allow the station called up by the central to make connection, even if another station 120 connected to the same line is calling, the wheel 14 is also provided with the contact-point 21. This contact-point is in alignment with contact-point 22 and is adapted to short-circuit the brushes 24^a at the same time that 125 the brushes 23 are short-circuited through the contact 22. When therefore central has brought the step-by-step movement of station 4 to the position that the alarm device of this station is actuated through the shunting of 130 the opposing coils, the brushes 24^a are also brought in electrical contact with each other, and as through the removing of the receiver from the lever this lever is brought in con-

tact with connecting-point 8 it establishes a second path between wire 2 and wire 1^a, this path consisting this time of wire 7, lever 5, contact 8, contact-brushes 24^a, connected electrically through contact 21, wire 24, receiver 4, and transmitter 3. The subscriber at station 4 therefore is enabled to converse with the subscriber calling.

It should be borne in mind that if the make-and-break device at the central is not provided with an automatic device to bring the lever always at the required time to its zero position then the operator has to perform the function either after the called-up subscriber has answered or if two subscribers on the same line communicate with each other after the communication has ceased. It is obvious, however, that in so adjusting the make-and-break device the same continues to a complete rotation to maintain all of the step-by-step mechanisms in unison or proper receiving condition.

From the drawings and explanations it is evident that in accordance with my invention a party-line may have any number of subscribers' stations connected thereto without one station interfering in the least with the other stations.

A party-line arranged and provided with the devices according to my invention has the following advantages: First, a subscriber connected to the line will always find the line open and unobstructed to his conversation; second, a subscriber on the line can call up central and can converse with central or other subscribers without fear that his conversation will be overheard by another subscriber; third, central can ring up any one of the subscribers connected to this line without the alarm devices of the other stations on the line being actuated; fourth, a subscriber on this line is able to converse with a second subscriber on the same line without a third subscriber being aware of this fact, and, fifth, central can call up and connect any one of the subscribers, no matter if the line is free or already in use, without disturbing the subscriber using the line or calling the attention of the subscribers not using the line.

As my invention relates only to party-lines and method of operating the same, but does not relate to the mode or method of connecting one line to the other, and as this part of the operation is well understood by persons versed in the art, and as my system of operating party-lines is applicable to the various systems in use to-day, no matter how far they differ in connecting two lines to each other, I have not illustrated or described either the usual spring-jacks, connecting-cords, and supervisory or other signals. In fact, I have omitted for the sake of clearness and better understanding all devices necessary or used in an exchange to-day and foreign to my own invention, and I have illustrated and described this invention only in so far as to enable persons versed in the art to make and

use the same, leaving it understood that different means may be employed to accomplish the same results without departing from the scope of my invention.

I have illustrated in Fig. 1 the step-by-step device as consisting of a movable wheel and an armature provided with a hinged pawl; but it is obvious that any of the well-known step-by-step devices may be substituted for the one illustrated. I have also described and illustrated the contact-points 21 and 22 as being part of the wheel, which is otherwise provided with an insulating-surface; but it is obvious that these contacts may consist of conducting-strips placed on or secured to the wheel; but in all cases care should be taken to present a smooth and even surface of the wheel to the brushes, as otherwise the movements of the wheel may be obstructed.

In Fig. 2 I have illustrated part of the circuit-wires 1 and 2 as being connected with battery B and being provided with the movable jacks 26 and 27. I did this for the purpose so as to show one method of bringing in electrical connection line-wire 2 with the make-and-break device; but it is obvious that when the usual jacks are employed this particular jack, consisting of the parts 26 and 27, can be dispensed with.

The battery B is made to represent the usual common battery to which the incoming circuits are connected. The battery B² is the special battery provided for the purpose of actuating the step-by-step movement.

I have illustrated the different stations as to be provided simply with the transmitter and receiver and have omitted the induction-coil usually employed. The office of this coil is well understood, and the same may be placed in the line or may be omitted from the same; but in some systems the insertion of the induction-coil is a necessity. I omitted to illustrate the same for the reason that my invention does not embrace any particular sending or receiving devices.

Having now described my invention, what I claim as new, and desire to secure by Letters Patent, is—

1. In a telephone system, the combination with a party-line, of a series of subscriber-stations connected in multiple arc therewith, each of said subscriber-stations including telephonic devices and a switch, and electromagnetic devices connected in series with the party-line and adapted to prevent the establishment of a circuit between the telephonic devices of each station and the switch thereat when such circuit has been established at one of the stations.

2. In a telephone system, the combination with a party-line, of a series of subscriber-stations connected in such manner with the party-line as to be normally open, each of said subscriber-stations including telephonic devices and a switch, and electromagnetic devices connected in series with the party-line and adapted to prevent the establish-

ment of a circuit between the telephonic devices of each station and the switch thereat when such circuit has been established at one of the stations.

5 3. In telephony, a party-line, two or more subscriber-stations connected in multiple are as to each other and said party-line, each of said stations provided with an electromagnetic device connected in series as to one of the line-wires constituting the circuit of said party-line, said electromagnetic device adapted to prevent the closing of the circuit in the remaining subscribers' stations, after the circuit in one of the subscriber-stations has been 15 established.

4. In a telephone system, the combination with a central station, and a party-line, of a series of subscriber-stations connected in multiple are to said line, a signal device for each 20 of said stations, each of said devices being provided with opposing pairs of coils so wound as to neutralize the effect of the current flowing through the signal device, means for shunting one of the pairs of said coils, and means 25 at the central station for actuating said shunting means.

5. In telephony, a party-line, two or more subscriber-stations connected to said party-line, an alarm device for each of said stations, 30 said alarm device provided with opposing coils so wound as to neutralize the effect of the current flowing through said alarm device, in combination with means to open or shunt the opposing coils of said alarm device 35 at the will of the operator located at the central or exchange.

6. In telephony, a party-line, two or more subscriber-stations connected in multiple are to said party-line, an alarm device provided 40 with opposing coils so as to neutralize the effect of the current flowing through said alarm device, a step-by-step movement for each of said alarm devices, and means located at the central or exchange to actuate said step-by-step movement, said step-by-step movement provided with means to close or open the shunt-circuit with which said alarm device is 45 provided.

7. In telephony, a party-line, two or more 50 subscriber-stations connected in multiple are as to said party-line, means at each station to connect electrically one line-wire of said party-line through the transmitter with the other line-wire of said party-line, and means at each 55 of said stations to connect the two line-wires, including the transmitter, of each station through a second circuit, normally broken but electrically connected at the will of the operator at the central or exchange.

8. In telephony, a party-line, two or more subscriber-stations connected in multiple are as to said line, a step-by-step movement for each subscriber-station, said step-by-step movement provided with means to close a 65 shunt-circuit of the alarm device with which said station is provided, and to connect the normally broken parts of a circuit adapted

to make connection between that part of the circuit connected to the lever and that part of the circuit connected to the transmitter. 70

9. In a telephone system, the combination with a party-line, and a series of subscriber-stations connected in multiple are therewith, of an auxiliary circuit formed by a shunt located at each of said stations and including 75 the transmitter and the receiver-hook, and means controlled by the central station and coöperating with the receiver-hook for opening and closing the auxiliary circuit.

10. In telephony, a party-line, two or more subscriber-stations connected in multiple are as to said line, means for each station to prevent the flow of the current through the telephonic devices placed at said station, if the circuit is closed at a second station, an alarm 80 device for each station, said alarm device provided with means to nullify the effect of the current impulses on the movable parts of said device, means for each of said alarm devices to make ineffective said nullifying 85 means, and means at each station to close the circuit of said party-lines including the telephonic devices at said station, through an auxiliary circuit with which each station is 90 provided. 95

11. In a telephone system, the combination with a party-line, of a series of subscriber-stations connected in multiple are with said line, an auxiliary circuit located at each of said stations and including a signal device, 100 means for controlling said auxiliary circuit, a second auxiliary circuit located at each of said stations and adapted to establish connection between the line and each of said stations independently of the other stations, said 105 second auxiliary circuit including the transmitter and the receiver-hook, and means coöperating with the receiver-hook for opening and closing the second auxiliary circuit.

12. In a telephone system, the combination 110 with a party-line, of a series of subscriber-stations connected in multiple are with said line, an auxiliary circuit located at each of said stations and including a signal device, means for controlling said auxiliary circuit, 115 a second auxiliary circuit located at each of said stations and adapted to establish connection between the line and each of said stations independently of the other stations, said second auxiliary circuit including the transmitter 120 and the receiver-hook, and means controlled by the central station and coöperating with the receiver-hook for opening and closing the second auxiliary circuit.

13. In a telephone system, the combination 125 with a party-line, of a series of subscriber-stations connected thereto and each including telephonic devices, an auxiliary circuit located at each of said stations and including a signal device, a step-by-step mechanism also 130 located at each of said stations and controlled by said auxiliary circuit, a second auxiliary circuit located at each of said stations and adapted to establish through the step-by-step

mechanism connection between the line and its stations independently of the other stations, and a make-and-break device located at the central station and controlling the auxiliary circuits of the several stations.

14. In a telephone system, the combination with a party-line, of a series of subscriber stations connected thereto and each including telephonic devices, a stationary contact, and 10 a switch, and an electromagnetic device for each of said stations connected to the line, said electromagnetic devices having their

armatures provided with means adapted to be interposed between the stationary contacts and the switches to prevent the establishment 15 of the telephonic circuits.

In testimony whereof I hereby sign my name, in the presence of two subscribing witnesses, this 12th day of April, A. D. 1901.

ISIDOR KITSEE.
